UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

RESETTING DEVICE FOR LOOM WEFT DETECTORS.

Application filed May 9, 1925. Serial No. 29,195.

This invention relates to improvements in weft detectors for looms equipped with regularly reciprocating transerrer arms such as shown in Patent No. 1,372,316 and an object of the invention is to provide means for resetting the plunger usually employed on such detectors after the same has had an indicating movement.

Another object of the invention is to provide positively operating means for engaging and moving a weft detector plunger of the type specified to normal position as the transerrer moves upwardly on an indicating beat of the loom.

A further object of the invention is to provide a weft detecting plunger resetting device which shall move to inoperative position after an indication of weft exhaustion to permit uninterrupted reciprocation of the transerrer and parts carried thereby.

With these and other objects in view which will appear as the description proceeds my invention resides in the combination and arrangement of parts hereinafter described and set forth in the claims.

In the accompanying drawings wherein I have shown one form of my invention,

Fig. 1 is a side elevation of portions of a replenishing mechanism taken from the central portions of a loom showing my invention applied thereto,

Fig. 2 is a detail rear elevation of parts of the transerrer and indicator levers looking in the direction of arrow 2, Fig. 1, parts being shown in section,

Fig. 3 is a fragmentary view similar to Fig. 2 and showing the parts in a different position,

Fig. 4 is an enlarged vertical section on line 4-4 of Fig. 2,

Fig. 5 is a detail of certain parts seen in Fig. 2 showing the plunger in position to be returned to normal position by the re-setter, and

Fig. 6 is a horizontal section on line 6-6 of Fig. 5, the pivoted re-setter corresponding to the dotted line position thereof shown in Fig. 5.

The invention comprises a regularly reciprocating transerrer arm having a detector and a plunger mounted thereon, the plunger being normally inoperative with respect to an indicating lever pivoted on the replenishing mechanism and being moved

into position to engage said indicating lever by the detector at indication of substantial exhaustion of weft. The invention relates more particularly to a plunger re-setter preferably pivotally mounted on the indicating lever to be engaged by the plunger after the latter has been moved to indicating position to swing about the center thereof to move said plunger longitudinally to normal position.

Referring more particularly to the drawings it will be seen that I have provided a loom frame 10, weft replenishing mechanism 11, and vertical slides 12 actuated by a color selector 13 movable longitudinally and angularly with respect to the replenishing mechanism. A transerrer 14 is pivoted as at 15 and is regularly reciprocated by a rod 16 controlled by a cam not shown.

The transerrer arm has mounted therein for sliding movement an indicating plunger 17 which at the time of indication of weft exhaustion is engaged by a weft detector 18 pivotally mounted as at 19 to a detector lever 20. Said lever 20 is mounted on stud 21 for angular movement with respect to the transerrer and has an offset finger 22 positioned for engagement with a normally raised but yielding actuator 23. Spring plunger 24 tends to hold stop screw 25 against a portion of the lever 20 to position the detector 18 with the toothed surfaces thereof laterally offset from the pivot 19.

A releasing plunger 26 is spring pressed toward the detector 18, being limited in motion toward said detector by the interengagement of pins 27 and 28 carried by the plunger 26 and transerrer arm 14, respectively. The plungers 17 and 26 are provided with notches 29 and 30, respectively, one of which is normally occupied by a ball lock 31. A compression spring 32 is interposed between a part of the detector lever 20 and a shoulder on plunger 17 to move the latter to the right as shown in Fig. 2 when the ball lock 31 is received by notch 30 in plunger 26.

The parts are normally in the position shown in Fig. 2 and in the operation of the mechanism thus far described the transerrer arm will be lowered every second pick of the loom when the shuttle is thereunder and so long as sufficient yarn is present detector 18 will be held against movement

along the bobbin W and finger 22 will depress actuator 23. When insufficient yarn is present the actuator will resist downward motion of the finger and cause the detector 18 to move longitudinally along the bobbin. As the transerrer nears the bottom of its stroke the detector will engage the releasing plunger 26 and move the same to the position shown in Fig. 3 so that the ball lock 19 may fall into notch 30 and release the plunger 17. The latter will thereupon be moved to the right and as the transerrer ascends will engage cam face 33 on an indicating lever 34 pivoted as at 35 to the replenishing mechanism to oscillate said lever 34 in a clockwise direction as viewed in Fig. 1 and actuate color selector 13 as described in the aforesaid patent. This part of the mechanism is substantially the same as shown in my co-pending application, Serial No. 25,642, filed April 24, 1925.

My present improvements relate to means for resetting the plunger 17 and by referring to Fig. 5 it will be seen that I have secured a U-shaped clip 50 to the indicating lever 34 and have mounted for free rotation therein a shaft 51 which extends beyond said clip 50 and is secured as by pins 52 to a resetting member 53 extending around the adjacent portion of indicating lever 34. A spring 54 is secured to the shaft 51 and clip 50 and tends to hold the resetter 53 in the position shown in full lines in Fig. 5. Said resetter 53 has a concave face 55 which is normally out of the path of the indicating plunger 17 when the latter rises with the transerrer on non-indicating movements. After the plunger 17 has been moved to the position shown in dotted lines in Fig. 2 and full lines in Fig. 5 it will be under the concave face 55 and as the transerrer 14 moves upwardly said plunger will engage the resetter and cause the latter to move about the shaft 51 to assume the position shown in dotted lines in Fig. 5, causing said plunger 17 to move inwardly until the notch 29 therein is in position to receive the ball lock 31 at which time the spring pressed plunger 26 will return to the normal position shown in Fig. 2 and raise the ball into notch 29 to lock the indicating plunger in non-indicating position. On the next downward movement of the transerrer arm the indicating plunger will release the resetter, which will be returned to normal inoperative position by spring 54. The resetter 53 is so proportioned that plunger 17 is moved beyond the adjacent faces of the indicating lever 34 so that as the transerrer reciprocates no part thereof will wear against the indicating lever.

From the foregoing it will be seen that I have provided a weft replenishing mechanism having a regularly reciprocated trans-

ferrer and indicator plunger mounted thereon with devices for positively engaging and resetting the plunger as the latter is moved upwardly on an indicating beat of the loom, the plunger being moved beyond the indicating lever with which it cooperates to avoid interreference therewith as the transerrer reciprocates. It will also be noted that the resetting member is returned to inoperative position on the next movement of the transerrer following indication of weft exhaustion.

Having thus described my invention it will be apparent that changes and modifications may be made therein by those skilled in the art without departing from the spirit and scope of the invention, and I do not wish to be limited to the details herein disclosed but what I claim is:

1. In a detector for loom weft replenishing mechanism, a regularly reciprocating transerrer arm, an indicating lever for the replenishing mechanism, a member mounted on said transerrer arm and movable at indication of exhaustion of weft into operative relationship with respect to the indicating lever, and means operable after said member has moved into operative relationship with respect to said lever to restore said member to normal non-indicating position and dependent upon the movement of the transerrer arm to move said member positively beyond the adjacent portions of the indicating lever.

2. In a detector for loom weft replenishing mechanism, a regularly reciprocating transerrer arm, an indicating lever for the replenishing mechanism, a member mounted on and movable with the transerrer to move into operative relationship with respect to the indicating lever at indication of weft exhaustion, and a resetting device normally out of operative relationship with the member and mounted for relative movement with respect to the indicating lever to engage the member and restore the same to normal position as the transerrer arm continues its upward movement.

3. In a detector for loom weft replenishing mechanism, a regularly reciprocating transerrer, an indicating lever for the replenishing mechanism, a plunger slidably mounted on said transerrer and movable at indication of weft exhaustion into operative position with respect to the indicating lever, and means carried by and movable with respect to the indicating lever to engage the plunger when in indicating position and restore the same to normal position as the transerrer ascends.

4. In a detector for loom weft replenishing mechanism, a regularly reciprocating transerrer, an indicating lever for the replenishing mechanism, a plunger slidably mounted on the transerrer and movable at

indication of weft exhaustion to operative position with respect to the indicating lever, and pivoted means other than the indicating lever to engage the plunger as the trans-
5 ferrer ascends and restore said plunger to normal position.

5. In a detector for loom weft replenishing mechanism, a regularly reciprocating transerrer arm, an indicating lever pivotally mounted on the replenishing mechanism independently of the transerrer, a plunger slidably mounted on the transerrer and movable at indication of weft exhaustion into operative position with respect to the 10 indicating lever, and a resetting device pivotally mounted on the indicating lever and movable therewith to engage the plunger as the transerrer ascends on an indicating pick of the loom to engage said plunger and restore the same to normal position.

6. In a detector for loom weft replenishing mechanism, a regularly reciprocating transerrer arm, an indicating plunger pivotally mounted with respect to the replenishing mechanism, a plunger slidably mounted on the transerrer arm and movable at indication of weft exhaustion into operative position with respect to the indicating lever, a resetting device pivotally mounted on the 25 indicating lever and normally out of the path of the plunger on non-indicating picks of the loom and engageable by said plunger on indicating picks of the loom to move pivotally with respect to the indicating lever and restore said plunger to normal position, and means to return said resetting device to a position out of the path of the plunger when the latter is in normal position.

7. In a weft detector for loom weft replenishing mechanism, a regularly reciprocating transerrer arm an indicating lever for the replenishing mechanism, a member mounted on and movable with the transerrer arm to move into operative relationship with respect to the indicating lever at indication of weft exhaustion, and a resetting device normally out of operative relationship with the member to engage the same and restore 45 said member to a position beyond adjacent portions of the indicating lever.

8. In a weft detector for loom weft replenishing mechanism, a regularly reciprocating transerrer arm an indicating lever for the replenishing mechanism, a member mounted on the transerrer arm and movable into operative relationship with the lever and normally locked in inoperative position, a weft detector on the transerrer arm operative at substantial exhaustion of weft to unlock the member, means independent of the detector 55 to move the member into operative position with respect to the indicating lever, and a resetting device operative after indication of weft exhaustion and against the action of said means to move the member to normal 60 position beyond adjacent portions of the indicating lever.

9. In a weft detector for looms, a regularly moving transerrer arm, an indicating lever for the replenishing mechanism, a control member for the lever mounted on the transerrer arm and normally locked in inoperative position with respect to the indicating lever and unlocked at substantial weft exhaustion, and a resetting device engaging 70 the member to restore the same to locked position to move said member beyond adjacent parts of the indicating lever.

10. In a weft detector for looms having a surface to be detected, a transerrer arm receiving a regular movement toward the surface to be detected, an indicating lever for the replenishing mechanism, a plunger on the transerrer arm, a lock for the plunger to hold the same normally inoperative with 80 respect to the indicating lever, resilient means tending to move the plunger into operative position with respect to the indicating lever when the plunger is unlocked, a detector 85 mounted on the transerrer arm and effective at substantial exhaustion of weft to engage the lock to unlock said plunger, and a resetting device for the plunger operative against the action of the resilient means and effective to restore said plunger to normal locked 90 position beyond adjacent portions of the indicating lever.

In testimony whereof I have hereunto affixed my signature.

ELBRIDGE R. HOLMES.
